UNITED STATES PATENT OFFICE.

BENJAMIN F. MIESSNER, OF SOUTH ORANGE, NEW JERSEY, ASSIGNOR TO MULTIPLE ELECTRIC PRODUCTS COMPANY, INC., OF NEW YORK, N. Y., A CORPORATION OF NEW YORK.

DESIGN FOR A SOUND AMPLIFIER.

Application filed February 23, 1924. Serial No. 8,702. Term of patent 14 years.

To all whom it may concern:

Be it known that I, BENJAMIN F. MIESSNER, a citizen of the United States of America, residing at South Orange, in the county of Essex and State of New Jersey, have invented a new, original, and ornamental Design for Sound Amplifiers, of which the following is a specification, reference being had to the accompanying drawing, forming part thereof.

Fig. 1 is a top plan view of a sound amplifier, showing my new design;

Fig. 2 is a front elevation of the sound amplifier shown in Fig. 1;

Fig. 3 is a side elevation of the sound amplifier shown in Fig. 1.

I claim:

The ornamental design for a sound amplifier, as shown.

In testimony whereof I hereto affix my signature.

BENJAMIN F. MIESSNER.
